UNITED STATES PATENT OFFICE.

HENRY W. PARTON, OF YONKERS, NEW YORK, ASSIGNEE TO THE ALEX.
SMITH & SONS CARPET COMPANY, OF SAME PLACE.

DESIGN FOR A CARPET.

SPECIFICATION forming part of Design No. 20,270, dated November 4, 1890.

Application filed October 10, 1890. Serial No. 367,627. Term of patent 3 $\frac{1}{2}$ years.

To all whom it may concern:

Be it known that I, HENRY W. PARTON, a citizen of the United States, residing at Yonkers, Westchester county, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

My design consists of the body A and the border B. The body A is composed of groups of flower forms representing water-lilies and buds. These flower forms rest upon large circular forms representing lily-pad leaves connected by their stems, all of which rest

upon a groundwork representing water. The border B is composed of an inner margin of grassy ornamentation, a middle portion of water-lily and bud forms resting upon large circular lily-pad leaf forms and an outer portion of lily-pad leaf forms and grasses, all of which rests upon a groundwork representing water.

What I claim as new, and desire to secure by Letters Patent, is—

1. The design for carpets, consisting of the body A, substantially as shown.
2. The design for carpets, consisting of the border B, substantially as shown.
3. The design for carpets, consisting of the body A and the border B, substantially as shown.

HENRY W. PARTON.
